UNITED STATES PATENT OFFICE.

HENRY H. VAUGHAN, OF MONTREAL, QUEBEC, CANADA.

REVERSE-GEAR.

1,101,976.

Specification of Letters Patent. Patented June 30, 1914.

Application filed April 1, 1912. Serial No. 687,908.

To all whom it may concern:

Be it known that I, HENRY H. VAUGHAN, of the city of Montreal, Province of Quebec, Dominion of Canada, have invented certain new and useful Improvements in Reverse-Gears; and I do hereby declare that the following is a full, clear, and exact description thereof.

My invention relates to appliances by which the operation of a power mechanism is reversed, and more particularly to the reversal of the direction of operation of a mechanism by the use of motive fluid means.

The invention has for its object to provide a reverse gear adapted to be locked against action or released and simultaneously effect the reversal of the operation of the mechanism to which it is applied; and the invention may be said broadly to consist of a controller, preferably unitary and manually-operated, in operative relation with motive-fluid means, and also in operative relation with a device for at times locking the motive fluid means against operation and at other times releasing the same, the said means being in operative relation with the power-mechanism to which it is applied.

Specifically stated the invention consists of means for the adjustment of a valve gear whereby either forward or backward movement or variation of the point of cut off, when moving in either direction may be effected.

For full comprehension, however, of my invention reference must be had to the accompanying drawings in which corresponding reference characters indicate the same parts, and wherein:

Figure 1 is a side elevation of a reverse gear of a locomotive containing my invention; Fig. 2 is a detail partial plan view illustrating particularly the indicating device; Fig. 3 is a detail sectional view taken on line A A Fig. 1; Figs. 4 and 5 are transverse vertical sectional views taken on line B B and C C respectively Fig. 2; Figs. 6, 7, 9 and 10 are transverse vertical sectional view taken on line D D, F F, M M and P P respectively Fig. 1; Fig. 8 is a detail enlarged view part elevation and part in vertical section of the operating handle and the means operatively connecting the same to the motive fluid means; Fig. 11 is a detail longitudinal vertical sectional view of the reversing valve taken on line S S Fig. 10.

In the drawings above described the invention is illustrated applied to the reverse gear of a locomotive in which it is usual to employ a pair of aligned cylinders, namely a resistance or dash-pot cylinder 2 and an operating cylinder 3 containing pistons 4 and 5 respectively connected by a piston rod from which adjustment is transmitted to the slide valve of the locomotive through suitable lever mechanism indicated at 6.

According to my invention the piston rod has a quick-thread screw 7 movable with the piston rod through openings in the arms 8 of a bracket 9 fastened, for convenience, to the boiler barrel. A nut 10 threaded upon this screw is located between these arms of the bracket and confined thereby against movement longitudinally relatively to the screw; and the upper side of these arms is curved and presents a sleeve 12 and carries a bracket 13 of inverted U-form and having its middle formed with an opening. The nut has an integral circumferential flange encircling the same with a series of notches 20 cut therein and engaged by a locking device preferably in the form of a pawl or latch 21 formed by or attached to the lower end of a rod 22, the upper end of which is coupled to a yoke 23. This yoke encircles the hub 24 of a bell-crank-lever the fulcrum pin whereof is carried by a bearing bracket 25 preferably fixed upon the boiler barrel. Between the hub and this bearing bracket an angular bracket 26 is fastened as at 27 to the face of the bearing bracket and the upper ends of the legs of this angular bracket has a pair of spaced quadrantal plates 30 rigidly carried thereby and provided with a pair of stops for limiting the throw of the lever in either direction, the lever being guided between these plates 30, and a latch 31 serving to retain the lever in any desired angular position along the guide plates and between the stops. An expansile coiled spring 40 bears between the upper end of the bracket 13 and a collar 41 formed rigidly upon the rod 22 and yieldingly retains the latter in its downward position and the latch in position to engage the notched flange on the nut. The forward side of the yoke has a pair of lugs 45 arranged to be engaged by lateral cam projections 50 upon the hub of the lever; the bearing bracket being braced by a pair of struts fastened at their upper ends thereto and at their lower ends to the bracket 9.

The means thus far described is a controller for manually locking the piston rod against longitudinal movement, and upon the movement of the bell-crank-lever to one side or the other to release the piston rod. In order that this controller will cause motive fluid to enter the motive fluid cylinder and the piston rod to be shifted in either direction simultaneously with the releasing thereof, a rod 50 connects the horizontal arm of the bell-crank-lever to one arm 51 of an angular lever, the other arm 52 whereof is bent outwardly and connected by a rod 53 to a lever arm 54 connected rigidly 15 to the stem of a plug valve 55. The chamber of this valve is secured to the underside of the cylinder and contains three parts and a motive fluid intake 59. The ports are indicated at 60, 61 and 62 and communicate 20 with ports 63, 64, 65 in the cylinder-casing and leading, respectively, to the opposite ends of the latter and to an exhaust port 70 midway of the length of the cylinder. The valve has a pair of circumferential ports 80 25 and 81 adapted to, respectively, when in different angular positions, effect a communication between the ports 60 or 61 and 59, and 60 or 61 and 62.

The dash pot is controlled by a valve 90 30 having a longitudinal series of diametrical ports 91 thereon, the chamber 92 of the valve being secured to the cylinder of the dash pot and having a pair of ports 93 with aligned inner ends terminating at the valve. A lever 94 fixed upon this valve is adjustable to different angular positions to vary 35 the capacity of the passage through the valve and therefore the resistance to the fluid passing through it.

40 A pointer 100 mounted on the piston rod at one end of the screw indicates on a scale the position of the piston-rod, and, consequently the reverse lever, the scale consisting of a graduated plate 101 while a sliding 45 plate 102, through an opening 103 in which the pointer projects is guided in its movement with the pointer by longitudinal guide plates 105.

Operation. Normally the hand lever 50 stands vertically and the cams 50 being displaced from the lugs on the yoke 23, the latter, and consequently the latch, are depressed by the spring 40 thus locking the nut 10 against rotation and the piston rod 55 against longitudinal movement. By swinging the hand lever to the right or left, looking at Fig. 1, the latch is raised through the medium of the cam 50, yoke 23 and rod 22 and the nut disengaged. Simultaneously 60 the valve 55 is swung to the position effecting a communication between the motive fluid supply port and port 60 or 61 and between the other port, at the opposite side of the piston, to the exhaust port 70. The 65 effect is that the piston is moved under the

energy of the motive fluid and the piston-rod, and with it the screw, is shifted through the nut 10 which, being released, is free to rotate and permit the passage of the screw. In this manner the lever mechanism 70 6 is caused to reverse or restore the normal condition of the slide valve of the locomotive.

Although I have disclosed this reverse-gear applied to a locomotive it may with 75 equal utility be applied to the alternate rotary movement of a member and locking of the same against movement relatively to a second member forming a part of other motive-fluid mechanism, without departing 80 from the spirit of my invention.

What I claim is as follows:—

1. Means for reversing the operation of a power mechanism, such means comprising a cylinder with a piston therein and a valve for controlling a motive fluid supply to the cylinder, a device distinct from the reversing mechanism for locking the piston against operation, a controller, means operatively connecting the said controller to the locking device, means whereby the said controller is operatively connected to the valve, and means operatively connecting the said piston to the mechanism to be reversed. 90

2. A reverse gear comprising an axially movable screw, a cylinder having a piston therein, a valve upon the cylinder, means operatively connecting the piston to the screw, a nut having the screw threaded therethrough, means retaining the nut against movement along the screw, a locking means locking the nut against rotation, a manually operated lever, means operatively connecting the lever to the locking means, and means whereby the said lever is operatively connected to the valve. 95

3. In combination with an object to be moved, a cylinder, a piston within the cylinder the said cylinder having supply and exhaust ports, a valve common to the said ports, a screw and a nut one movable relatively to the other and longitudinally relatively to the screw, means connecting the movable part to the object to be moved, means locking the nut, a lever, means operatively connecting the lever to the locking means, and means whereby the said lever is operatively connected to the valve. 110

4. A reverse-gear comprising an axially movable screw, a cylinder having a piston therein, a valve upon the cylinder, means operatively connecting the piston to the screw, means for regulating the speed of axial movement of the screw, a nut having the screw threaded therethrough, means retaining the nut against movement along the screw, displaceable means locking the nut against rotation, a manually operated lever, means operatively connecting the lever to the locking means, and means whereby the 125 130

said lever is operatively connected to the said valve.

5. In combination with an object to be moved, a cylinder, a piston within the cylinder, the said cylinder having supply and exhaust ports, a valve common to the said ports, a screw and a nut one movable relatively to the other and longitudinally relatively to the screw, means connecting the movable part to the object to be moved, means locking the nut, a manually operated lever, means operatively connecting the manually operated lever to the locking means, and means whereby the said lever is operatively connected to the valve.

6. In combination with an object to be moved, a screw operatively connected to the object, means for moving the screw longitudinally, a nut upon the screw, means retaining the nut against longitudinal movement relatively to the screw, a device for locking the nut against rotation, and controlling means operatively connected to the locking device and to the means for moving the screw, such controlling means being adapted at times to simultaneously release the nut and move the screw, and at other times lock the nut and the screw.

7. In combination with an object to be moved, a screw operatively connected to the object, means for moving the screw longitudinally, a nut upon the screw and in permanent engagement therewith means retaining the nut against longitudinal movement relatively to the screw, a device for locking the nut against rotation, and controlling means operatively connected to the locking device and to the means for moving the screw for the purpose of at all times simultaneously releasing the nut and moving the screw and at other times locking the nut and screw.

8. In combination with an object to be moved, a motive-fluid cylinder containing a reciprocating piston, a piston rod connected at its outer end to the object, valvular means controlling the supply of motive fluid to the cylinder, a pair of interengaging members consisting of a screw and a nut upon the screw, means whereby one of the said members is connected to and moves in unison with the piston rod, means whereby relative movement between the nut and screw in a longitudinal direction with relation to the screw is prevented, a displaceable device for locking the nut against rotation, and controlling means operatively connected to the valvular mechanism and locking device.

9. In combination with an object to be moved, a motive-fluid cylinder containing a reciprocating piston, a piston rod connected at its outer end to the object, valvular means containing the supply of motive-fluid to the cylinder, a pair of interengaging members consisting of a screw and a nut upon the

screw, means whereby one of the said members is connected to and moved in unison with the piston rod, means whereby relative movement between the nut and screw in a longitudinal direction with relation to the screw is prevented, a displaceable device for locking the nut against rotation, and manually operated controlling means operatively connected to the valvular mechanism and locking device.

10. In combination with an object to be moved, a motive-fluid cylinder containing a reciprocating piston, a piston rod connected at its outer end to the object, valvular means controlling the supply of motive-fluid to the cylinder, a pair of interengaging members consisting of a screw and a nut upon the screw and permanently engaging therewith, means whereby one of the said members is connected to and moves in unison with the piston rod, means whereby relative movement between the nut and screw in a longitudinal direction with relation to the screw is prevented, a displaceable device for locking the nut against rotation, and controlling means operatively connected to the valvular mechanism and locking device.

11. In combination with an object to be moved, a motive fluid cylinder containing a reciprocating piston, a piston rod connected at its outer end to the object, valvular means controlling the supply of motive fluid to the cylinder, a pair of interengaging members consisting of a screw and a nut upon the screw, means whereby one of the said members is connected to and moves in unison with the piston rod, means whereby relative movement between the nut and screw in a longitudinal direction with relation to the screw is prevented, a displaceable device for locking the nut against rotation, and manually operated unitary controlling means operatively connected to the valvular mechanism and locking device.

12. In combination with an object to be moved, a motive fluid cylinder containing a reciprocating piston, a piston rod connected at its outer end to the object, valvular means controlling the supply of motive-fluid to the cylinder, a pair of interengaging members consisting of a screw and a nut upon the screw and permanently engaging therewith connecting means whereby one of the said members is connected to and moves in unison with the piston rod, means whereby relative movement between the nut and screw in a longitudinal direction with relation to the screw is prevented, a displaceable device for locking the nut against rotation, and manually operated unitary controlling means operatively connected to the valvular mechanism and locking device.

13. In combination with an object to be moved, a motive-fluid cylinder containing a reciprocating piston, a piston rod connected

to the object, valvular means controlling the supply of motive-fluid to the cylinder, a screw forming a component part of the piston rod, a nut upon the screw, means whereby the nut is held against displacement with the piston rod while free to rotate, a displaceable device for locking the nut against rotation, and controlling means operatively connected to the valvular mechanism and locking device.

14. In combination with an object to be moved, a motive fluid cylinder containing a reciprocatory piston, a dash pot consisting of a cylinder containing a piston and having 15 a by-pass port, a piston rod connected at its opposite ends to the respective pistons and between its ends to the object, valvular means controlling the supply of motive fluid to the cylinder, a screw forming the component part of the piston rod, a nut upon the screw means whereby the nut is held against displacement with the piston rod while free to rotate, a displaceable device for locking the nut against rotation, and 20 controlling means operatively connected to the valvular mechanism and locking device.

15. In combination with an object to be moved, a motive-fluid cylinder containing a reciprocatory piston, a piston rod connected 30 to the object, valvular means controlling the supply of motive fluid to the cylinder, a screw forming a component part of the piston rod, a nut upon the screw and having an annular circumferential notched flange, means whereby the nut is held against displacement with the piston rod while free to 35 rotate, a locking pawl engaging the notched flange, a hand-lever, a rod and cam-mechanism connecting the lever to the pawl, a 40 spring yieldingly retaining the pawl in engagement with the notched flange, and lever mechanism operatively connecting the hand lever to the valvular mechanism.

16. In combination with an object to be moved, a motive-fluid cylinder containing a reciprocatory piston, a dash pot consisting of a cylinder containing a piston and having 45 a by-pass port, a piston rod connected at its opposite ends to the respective pistons and between its ends to the object, valvular means controlling the supply of motive-fluid to the cylinder, a quick-threaded screw forming a component part of the piston rod, a nut upon the screw and having an annular 50 circumferential notched flange, means whereby the nut is held against displacement with the piston rod while free to rotate, a locking pawl engaging the notched flange, a hand-lever, a rod and cam-mechanism connecting 55 the lever to the pawl, a spring yieldingly retaining the pawl in engagement with the notched flange, and lever mechanism operatively connecting the hand lever to the valvular mechanism.

17. In a locomotive, the combination with

the reverse gear thereof including lever mechanism, of a motive fluid cylinder containing a piston, a piston rod connected to the said lever mechanism, valvular means controlling the supply of motive fluid to the cylinder, a screw forming a component part of the piston rod, a nut upon the screw, means whereby the nut is held against displacement with the piston rod while free to rotate, a displaceable device for locking the nut against rotation, and controlling means operatively connected to the valvular mechanism and locking device. 75

18. In a locomotive, the combination with the reverse gear thereof including lever mechanism, of a motive fluid cylinder containing a piston, a piston rod connected to the said lever mechanism, a valvular means controlling the supply of motive fluid to the cylinder, a screw forming a component part 80 of the piston rod, a nut upon the screw and having an annular circumferential notched flange, means whereby the nut is held against displacement with the piston rod while free to rotate, a locking pawl engaging the 85 notched flange, a hand-lever, a rod and cam-mechanism connecting the lever to the pawl, a spring yieldingly retaining the pawl in engagement with the notched flange, and lever mechanism operatively connecting the hand 90 lever to the valvular mechanism. 95

19. In a locomotive, the combination with the reverse gear thereof including lever mechanism, of a motive fluid cylinder containing a piston, a dash pot consisting of a cylinder containing a piston and having a by-pass port, a piston rod connected at its opposite ends to the respective pistons and between its ends to the said lever mechanism, valvular means controlling the supply of 100 motive fluid to the cylinder, a quick-threaded screw forming a component part of the piston rod, a nut upon the screw, and having an annular circumferential notched flange, means whereby the nut is held against displacement with the piston rod while free to 105 rotate, a locking pawl engaging the notched flange, a hand-lever, a rod and cam-mechanism connecting the lever to the pawl, a spring yieldingly retaining the pawl in engagement with the notched flange, and lever mechanism operatively connecting the hand lever to the valvular mechanism. 110

20. In a locomotive, the combination with the reverse gear thereof including lever 120 mechanism, of a motive fluid cylinder containing a piston, a piston rod connected to the said lever mechanism, valvular means controlling the supply of motive fluid to the cylinder, a screw forming a component part of the piston rod, a nut upon the screw, means whereby the nut is held against displacement with the piston rod while free to rotate, a displaceable device for locking 125 the nut against rotation, and controlling 130

means operatively connected to the valvular mechanism and locking device, a graduated member carried by a fixed part of the locomotive, and a pointer registering with the 5 graduations and carried by the piston rod.

21. In a locomotive, the combination with the reverse gear thereof including lever mechanism, of a motive fluid cylinder containing a piston, a dash pot consisting of a 10 cylinder containing a piston and having a by-pass port, a piston rod connected at its opposite ends to the respective pistons and between its ends to the said lever mechanism, valvular means controlling the supply of motive fluid to the cylinder, a quick-threaded screw forming a component part of the piston rod, a nut upon the screw, and having an annular circumferential notched 15 flange, means whereby the nut is held against

displacement with the piston rod while free 20 to rotate, a locking pawl engaging the notched flange, a hand-lever, a rod and cam-mechanism connecting the lever to the pawl, a spring yieldingly retaining the pawl in engagement with the notched flange, and lever mechanism operatively connecting the hand lever to the valvular mechanism, a graduated member carried by a fixed part of the locomotive, and a pointer registering with the graduations and carried by the pis- 25 ton rod.

In testimony whereof I have signed my name to this specification in the presence of two witnesses.

HENRY H. VAUGHAN.
